FOLDING STAIRWAY

Paul V. Harmon, Nashville, Tenn., assignor to Precision Parts Corporation, Nashville, Tenn., a corporation of Tennessee

Application March 31, 1952, Serial No. 279,581

6 Claims. (Cl. 228—50)

This invention relates to folding stairways and is a continuation in part of my co-pending application Serial No. 751,107 filed May 28, 1947, now abandoned.

Folding stairways are in more or less common use for providing convenient access to attics without requiring the space occupied by permanent stairs. Folding stairs are movable to upper inoperative positions within a frame fixed in the ceiling and usually are counterbalanced to remain in such normal position by spring means.

While spring counterbalancing means are fully operative and practicable they possess several definite disadvantages. In the first place they are relatively expensive to manufacture and the springs sometimes break due to crystallization of the metal. Moreover, spring devices used for this purpose are loaded to the maximum extent when the stairway is unfolded and to the minimum extent when the stairway is in the folded inoperative position. Spring counterbalanced folding stairways some years ago superseded the original stairways of this type wherein the stairway was rigid from end to end and substantially longer than the frame mounted in the ceiling. It was the common practice to slide such stairways upwardly endwise thereof and then to swing the lower end of the stairway about a horizontal rocking axis to move the stairway to inoperative position. The upper end of such stairway counterbalanced the lower end thereof and thus held the stairway folded, but the end of the stairway acting as the counterbalance occupied substantial attic floor space which had to be kept clear in order for the stairway to fold. This objection is overcome by the spring counterbalancing devices now in common use but these devices are disadvantageous for many reasons, several of which have been mentioned above.

An important object of the present invention is to provide a folding stairway in which counterbalancing spring devices are completely eliminated and the stairway is counterweighted to be held in folded or inoperative position without requiring any free floor space in the attic, the entire stairway and its counterbalancing means being retained wholly or substantially wholly within the limits of the ceiling frame.

A further object is to provide such a stairway wherein a simple type of counterweighting means is employed and wherein such means provides little or no counterweighting action when the stairway is unfolded but provides the maximum counterbalancing forces when the stairway is folded, this being the condition in which maximum counterweighting is desired.

A further object is to provide such a stairway which can be moved between folded and unfolded positions with a minimum amount of effort, thus rendering the stairway operative by a small child, the force necessary for swinging the structure between its two positions being materially reduced by a highly simple but effective anti-friction bearing means.

A further object is to provide such a structure wherein the counterweighting means substantially overbalances

2

the stairway as the folded positions of the parts are approached and wherein the stair structure substantially overbalances the counterweighting means as the stair structure approaches the unfolded positions of the parts, thus providing a high degree of stability of the parts in either of the two positions referred to.

A further object is to provide a folding stairway of the character referred to wherein the substantial overbalancing of the parts in the two positions referred to and the extreme ease of movement of the parts tends to cause the ladder to swing too rapidly toward either limit of movement, and to provide in conjunction with the structure a novel type of dash pot control means to tend to retard movement of the parts as they approach either limit of movement while providing relatively unrestricted movement of the parts away from the two positions referred to and intermediate such positions.

Other objects and advantages of the invention will become apparent during the course of the following description. In the drawings I have shown one embodiment of the invention. In this showing:

Fig. 1 is a perspective view of the stairway showing the parts in solid lines in the fully unfolded operative positions of the parts with two of the stair sections shown partly folded in dotted lines;

Fig. 2 is a vertical longitudinal sectional view through the structure showing the parts in the fully closed or folded positions;

Fig. 3 is a transverse vertical sectional view taken substantially on line 3—3 of Fig. 2;

Fig. 4 is an enlarged fragmentary side elevation of a supporting bracket and associated elements showing in section the dash pot associated therewith;

Fig. 5 is an enlarged fragmentary side elevation, at a smaller scale than Fig. 4, showing one of the counterweight levers and associated parts, a portion of the lever arm being broken away;

Fig. 6 is a section of line 6—6 of Fig. 5, parts being shown in elevation;

Fig. 7 is an enlarged detailed sectional view on line 7—7 of Fig. 6; and

Fig. 8 is a fragmentary perspective view of one of the abutment stops and associated elements.

Referring to Fig. 1, the numeral 10 designates as a whole a ceiling frame comprising vertically arranged longitudinal side frame members 11 and similarly arranged end frame members 12 defining an access opening 13. The lower edge of the frame is provided with strips forming a rectangular trim 14 which lies against the ceiling of a hall or room with the frame 10 projecting upwardly therethrough with its upper edge substantially flush with the floor above. The opening 13 is normally closed by a panel 16 hinged to the frame 10 as at 17. The panel 16 preferably is transversely braced by means of batten strips 18.

The structure further comprises a plurality of ladder or stair sections respectively indicated by the numerals 20, 21 and 22 each of which comprises spaced side rails 23 connected by steps or rungs 24 equidistantly spaced to form a stairway when the parts are fully unfolded as shown in solid lines in Fig. 1. The stair section 20 is the longest of the three sections, being almost co-extensive in length with the panel 16, and the side rails 23 of such section are fixed to the strips 18 in any suitable manner, as will be apparent. The side rails of the stair sections 20 and 21 are hinged to each other at the top edges thereof when the sections are unfolded, as indicated by the numeral 26. The lower edges of the sections 21 and 22 are hinged to each other as at 27, thus permitting the sections 21 and 22 to be swung upwardly in hinged relation to each other and to the section 20, as suggested in

dotted lines in Fig. 1, to assume the fully folded positions shown in Fig. 2. Each of the step members 24 is provided with an antiskid tread member 28 which may be formed of rubber or any other suitable material.

A hand rail 30 is preferably provided for the stair section 20, this rail being connected to one of the side rails 23 of the section 20 by posts or the like 31.

Novel means is provided for counterbalancing the stair structure described, to hold the latter in the fully folded position shown in Fig. 2. Each longitudinal frame member 11 carries fixed thereto as at 34 a plate 35 forming part of a bearing casting projecting substantially above the frame 10. Each plate 35 at its upper end carries a cylindrical bearing 36. The bearings of the two plates 35 obviously are arranged in axial alignment. The two bearings are identical and project outwardly of the plates 35 as clearly shown in Figs. 3 and 6.

A counterbalancing lever indicated as a whole by the numeral 37 is associated with each bearing 36, the two levers 37 being identical with each other. Each lever 37 comprises a lower casting 38, which may be made conveniently and economically of aluminum, and this casting has a circular lower end 39 overlying one end of one of the bearings 36, as shown in Fig. 6. Each casting 38 carries a laterally projecting trunnion 40 extending through the associated bearing 36. Each trunnion is smaller in diameter than the internal diameter of the associated bearing to provide an annular space 41 (Fig. 7) in which is arranged a plurality of needle or roller bearings 42. These bearings are simply sections of a circular rod suitably cut to length and each has one end abutting the circular end 39 of the associated counterweight lever.

At the inner face of each bearing 36 is arranged the circular end 45 of an arm 46 and receiving a reduced tapered end 47 of the trunnion 40. The body of the trunnion terminates preferably very slightly beyond the plane of the inner face of the bearing 36 to permit the arm 46 to be clamped against the trunnion by a nut 48 without causing the arm 46 to bind against the bearing 36. The circular end 45 of the arm 46 is adapted to abut the adjacent ends of the bearings 42. It will be apparent that the bearings 42 may be made very economically and require no keepers since the bearings are retained in position by the members 39 and 45. In view of the fact that the stair structure as a whole merely rocks but does not rotate, and ordinarily is operated only occasionally, it is not necessary that the bearings be made of hardened steel or that they be associated with perfectly machined surfaces. The provision of the bearings, therefore, is economical and an important addition to the structure since it permits it to swing with extreme ease and freedom between its two positions.

Each casting 38 acts as a socket to receive one end of a rod or lever arm 50 as shown in Fig. 6, a set screw 51 preferably being provided to fix the elements 38 and 50 with respect to each other. The end of each rod or arm 50 carries a counterweight element 52 which may be of any suitable form or material. It has been found highly effective and economical to mold the counterweights 50 of cement directly on the free ends of the arms 50.

Each arm 46 has fixed thereto, as at 55, an arm 56 projecting in the opposite direction with respect to the trunnion 40 from the counterweight 52. Obviously an arm 56 is connected to each arm 46 and the remote end of each arm 56 is pivotally connected, as at 57, to one end of a link 58. The other end of each link 58 is pivotally connected, as at 59, to one of the side frame members 23 of the stair section 20. From the foregoing description it will be apparent that each counterweight arm 37, its trunnion 40 and arms 46 and 56 form a rigid unit which swings about the axis of the associated trunnion 40.

The inner face of each side frame member 11 carries a plate 62 to which is fixed an abutment stop 63 preferably formed of resilient material. The plates 62 are preferably

secured in position after installation of the device in such positions that the abutment stops 63 contact with the arms 58, as shown in Fig. 1, when the stair sections 20, 21 and 22 are in alignment with each other.

5 In order to control the movements of the parts described above, a novel type of dash pot indicated as a whole by the numeral 66 is employed, preferably in conjunction with each counterbalancing structure. Referring to Fig. 4, the circular end 39 of each counterweight arm is provided with a radially extending lug 67, preferably adjacent the inner face of the circular portion 39 as shown in Fig. 3. The lug 67 is pivotally connected by a bolt 68 to the upper end of a plunger rod 69 carrying the plunger 70 reciprocable in a cylinder 71. This cylinder at its lower end, and preferably in close proximity to the adjacent plate 35, is provided with a lug 72. A bolt 73 passes through this lug and through the adjacent plate 35, the latter preferably being provided with an integral pad 74 projecting outwardly from the plate to engage the inner face of the lug 72.

10 The cylinder 71 is closed at one end, as at 76, and is provided with a cap 77 at its other end apertured for the passage therethrough of the rod 69. The plunger 70 comprises a pair of sealing cups 78 clamped together by plates 79 suitably mounted on the rod 69 and provided with small bleed openings 80 affording restricted communication at all times between the cylinder spaces on opposite sides of the plunger 70. Intermediate its ends, the cylinder 71 is provided with one or more openings 15 81. Preferably a plurality of such openings is employed, circumferentially spaced around the cylinder, and affording relatively free communication between the atmosphere and one end of the interior of the cylinder 71 when the openings 81 are not covered by the plunger 70. The 20 purpose of this arrangement will be described below.

Operation

The parts normally occupy the folded positions shown in Fig. 2 and it will be noted that the bottom of the panel 16 is flush with the lower face of the trim 14. The surfaces of these elements are preferably smooth and when finished to correspond to the ceiling of the room, the structure is hardly visible. It also will be noted in Fig. 2 that all of the operating parts of the structure lie wholly 25 within the limits of the frame 10. Referring to Fig. 3, it will be noted that the counterweights 52 project only slightly beyond the transverse limits of the frame 10 and trim 14. In some installations slightly longer counterweight arms 37 are required, in which case the counterweights will project very slightly beyond the cross members 12. In no case, however, is there any substantial protrusion of any of the parts beyond the limits of the frame 10 either longitudinally or transversely thereof and, 30 accordingly, the structure does not occupy any attic floor space, which is highly disadvantageous.

35 The stair structure readily may be opened for use by pulling downwardly on the free end of the panel 16. A chain or pull cord (not shown), which is of course conventional, conveniently may be connected to the free end 40 of the panel 16. The panel is swung downwardly until it occupies the position shown in Fig. 1, at which point the arms 56 will be brought into engagement with the abutment stops 63 to limit further movement of the counterbalancing means and all of the elements connected 45 thereto. It will be noted that the links 58 and their associated arms 56 are arranged only at relatively slight angles with respect to each other and, accordingly, the component of force acting horizontally against the abutment stops 63 is minimized. As a matter of fact in many 50 installations the arms 56 and links 58 are even more nearly in alignment to further minimize horizontal components of force against the stops 63. Therefore, there is no great force exerted against these stops when the 55 stairway is in use and by using resilient elements 63, the structure reaches its opened position noiselessly.

The structure having been opened in the manner described, the operator will then proceed to unfold the stair sections 21 and 22 by reaching up and grasping a step of the section 22 or the side rails thereof and pulling outwardly away from the main stair section 20. The sections 21 and 22 are then lowered to the solid line positions shown in Fig. 1, and the stairway is ready for use. The operations referred to are obviously reversed to fold or close the stairway, it merely being necessary to fold the sections 21 and 22 back upon the section 20 and then to push upwardly on the free end of the panel 16. In this connection it will be noted that while the angle between the arms 56 and links 58 is minimized for the purpose stated, it is preferable to preserve a slight angularity to prevent approaching a dead-centering of the various pivot axes. Dead-centering would not actually occur even with alignment of the arms 56 and links 58 because of the offsetting of the axes of the trunnions 40 from the axes of the pivot members 57 and 59, but slightly greater force would be required to close the structure than is true with the arrangement shown.

It will be apparent that the counterweight arms have their greatest moment in the region of the closed position of the parts shown in Fig. 2, and accordingly the counterweights are most effective for holding the stairway in closed position. On the other hand, the most effective moment of the stair structure is in the region of the open position of the parts since under such conditions the moments of the counterweight levers are negligible, since these levers are in the nearly vertical positions shown in solid lines in Figs. 1 and 5. Therefore the structure is very greatly overbalanced and biased to remain in either of its two positions.

The bearings 42, as stated, provide a simple and highly economical antifriction means for minimizing the effort required to swing the stair structure between its two positions. This means is so effective that a very small child can operate the stairway between its two positions without assistance. Simple rod sections are employed for the bearings 42 and no keepers or retainers are necessary since the ends of the bearing rollers abut the members 39 and 45. In the assembling of the parts, each trunnion is inserted in its bearing 36, the bearing rollers are inserted in position, and the circular portion 45 of the arm 46 is slipped over the tapered end 47 and the nut 48 is applied and tightened. The arm end 45 binds on the tapered trunnion section 47 and preferably also binds against the adjacent shoulder of the trunnion 40 without binding against the bearing 36.

As stated, the antifriction rollers materially increase the degree of ease with which the stair structure is swung between its two positions. As a matter of fact, this degree of ease is so great that it may be disadvantageous. As stated, the counterweights greatly overbalance the stair structure in the closed position and as the panel 16 is pulled downwardly the counterweights 52 swing upwardly and their effective moment arms progressively decrease and at an intermediate position of the parts the counterweights and stair structure balance each other. During this intermediate range of movement the momentum of the parts may materially increase if a substantial force has been applied to the panel 16 in pulling it downwardly. This generates a substantial inertia which carries the parts too rapidly to the fully opened position and the arms 56 will strike the abutment stops 63 with substantial force. Conversely, the closing of the structure, if performed with substantial force, will generate inertia in the intermediate positions of the parts which will carry them too rapidly to closed position and the sudden stopping of the parts in the closed position may strain the parts and cause substantial noise. The distinct advantage of the antifriction bearings is retained while eliminating the possible disadvantage thereof by providing the dash pots 66. Referring to Fig. 4 in which the parts are shown in the open position of the stairway, the plunger 70 is at the lower end of its stroke.

The upper end of the cylinder 71 is open to the atmosphere through the ports 81. When the closing movement of the stairway is performed, the circular member 39 rotates counterclockwise as viewed in Fig. 4 and the plunger 70 moves upwardly and this movement is quite free due to the presence of the ports 81. In an intermediate position of the parts, the plunger 70 will close the ports 81 at the upper end of the cylinder 71, thus trapping air therein and this air can escape only through the bleed ports 80 into the cylinder 71 beneath the plunger. If movement of the parts is quite rapid, the restricted flow of air through the plunger ports 80 will build up substantial pressure in the upper end of the cylinder 71 thus cushioning the movement of the parts. The inertia of the parts will carry the plunger 70 beyond the ports 81 and there will be a progressive building up of pressure in the upper end of the cylinder 71 as the effective moments of the stair parts decrease while the moments of the counterweight arms increase. This building up of pressure retards movement of the parts as the latter approach the fully closed position.

As stated, the same inertia conditions will be present in both the opening and closing movements of the stairway. The dash pots 66 operate in the same manner in both movements of the parts. As the stair is opened, the moments of the stair parts swinging downwardly relatively increase as the moments of the counterweight arms decrease, and during such time the plunger 70 will be moving downwardly from the top of the cylinder 71. At an intermediate point, the ports 81 will be closed to the lower end of the cylinder 71 and pressure will be built up therein to an extent depending on the speed of movement of the parts. If movement is too rapid, air cannot escape through openings 80 with sufficient rapidity to maintain atmospheric pressure in the lower end of the cylinder 71 and the increase in pressure will retard the movement of the parts and thus prevent the stair structure from reaching the open position at too great a speed of movement.

Thus it will be apparent that the simple bearing means employed provides for an extremely free movement of the parts. If this movement takes place relatively slowly or is manually retarded in the last portion of the travel, the dash pots will remain substantially ineffective for retarding the movement of the parts. The dash pots therefore act automatically only when the speed of movement of the parts is too great, to prevent the parts from reaching either open or closed position at too great a speed of movement.

As previously stated, there is substantial over-balancing of the parts in either of the positions thereof and since the counterbalancing effect of the counterweights is substantially negligible when the stairway is in use, the stair structure may be made as light as structural requirements permit. For example, the stairway may be made of magnesium or aluminum and regardless of the lightness of its weight, it will remain in open position.

The structure employs the simplicity of counterbalancing without the disadvantage of earlier folding stair structures wherein substantial attic space had to remain free to accommodate one end of the ladder. The structure also eliminates the substantial disadvantages incident to the use of counterbalancing springs, there being no springs of any kind employed with the structure.

I claim:

1. A folding stairway comprising a generally rectangular open frame adapted to be mounted in a ceiling, a plurality of ladder sections hinged end to end to swing to operative positions in alignment with each other and to inoperative positions folded and superimposed relative to each other, one of said ladder sections being hinged to said frame, a bracket fixed to each side of said frame intermediate the ends thereof and projecting substantially thereabove, the upper ends of said brackets being provided with aligned bearings, a lever provided intermediate its ends with a trunnion mounted in each bearing, one end of each lever having a counterweight, a link piv-

totally connected at one end to the other end of each lever and having its opposite end pivotally connected to one side of said one ladder section at a point remote from the hinged connection thereof with said frame, said ladder sections being mounted to swing, when folded, to an upper inoperative position within said frame and to a lower operative position, when said sections are unfolded, said counterweights, when said ladder sections are in their lower operative positions, projecting upwardly from said bearings to provide negligible moment arms tending to turn said levers, said counterweights, when said ladder sections are in said inoperative positions, projecting to positions adjacent one end of said frame to exert substantially their maximum moment arms to tend to hold said ladder sections in closed positions, and a dash pot comprising a cylinder and a single plunger therein forming a pair of elements one of which is connected to a fixed pivot carried by one of said brackets and the other of which is pivotally connected to one of said levers eccentrically of its trunnion, said cylinder intermediate its ends being vented to the atmosphere whereby said plunger is freely relatively movable in said cylinder away from either end thereof and retarded in its movement as it approaches either end of said cylinder.

2. A folding stairway comprising a generally rectangular open frame adapted to be mounted in a ceiling, a ladder structure pivotally connected to said frame at one end thereof to swing between an upper inoperative position and a lower operative position a bracket fixed to each side of said frame intermediate the ends thereof, said brackets projecting substantially above said frame and being provided at their upper ends with aligned bearings, a pair of levers each provided intermediate its ends with a trunnion rotatable in one of said bearings, one end of each lever being arranged outwardly of its associated bearing and being provided on its end with a counterweight, the other end of each lever lying within its associated bearing, and a link connected at one end to said other end of each of said levers, said links being pivotally connected at their other ends to said ladder structure at points remote from the pivotal connection of said ladder structure with said frame, said one end of each lever, when said ladder structure is in its upper inoperative position, extending in proximity to but not substantially beyond one end of said frame to provide substantially maximum moment arms tending to hold said stair structure in such position, said counterweights being substantially above said bearings when said ladder structure is in its lower operative position whereby the moment arm of said one end of each lever is substantially negligible when said ladder sections are in such position, said counterweights being movable in vertical planes adjacent but wholly outwardly of the sides of said frame.

3. A folding stairway comprising a generally rectangular open frame adapted to be mounted in a ceiling, a ladder structure pivotally connected to said frame at one end thereof to swing between an upper inoperative position and a lower operative position, a bracket fixed to each side of said frame intermediate the ends thereof, said brackets projecting substantially above said frame and being provided at their upper ends with aligned bearings, a pair of levers each provided intermediate its ends with a trunnion rotatable in one of said bearings, one end of each lever being arranged outwardly of its associated bearing and being provided on its end with a counterweight, the other end of each lever lying within its associated bearing, a link connected at one end to said other end of each of said levers, said links being pivotally connected at their other ends to said ladder structure at points remote from the pivotal connection of said ladder structure with said frame, said one end of each lever, when said ladder structure is in its upper inoperative position, extending in proximity to but not substantially beyond one end of said frame to provide substantially maximum moment arms tending to hold said stair struc-

ture in such position, said counterweights being substantially above said bearings when said ladder structure is in its lower operative position whereby the moment arm of said one end of each lever is substantially negligible

5 when said ladder sections are in such position, said counterweights being movable in vertical planes adjacent but wholly outwardly of the sides of said frame, and a dash pot comprising a cylinder and a single piston forming a pair of elements one of which is pivoted to a fixed point and the other of which is pivoted to one of said levers eccentrically of its trunnion, said cylinder intermediate its ends being vented to the atmosphere whereby said piston is movable relatively freely in said cylinder away from either end thereof, said piston being apertured to afford restricted communication between opposite ends of said cylinder whereby said piston is free to approach either end of said cylinder if moved relatively slowly but is cushioned in such movement if moved relatively rapidly.

20 4. A folding stairway comprising a generally rectangular open frame adapted to be mounted in a ceiling, a ladder structure pivotally connected at one end to one end of said frame to swing between an upper inoperative position and a lower operative position, a bracket carried by each side of said frame intermediate the ends thereof and projecting substantially above said frame, said brackets being provided at their upper ends with aligned bearings, a pair of levers each provided intermediate its ends with a trunnion mounted in one of said bearings, each lever having one end arranged outwardly of and in contact with the outer end of one bearing and having its other end in contact with the inner end of such bearing, a counterweight connected to said one end of each lever, a link pivotally connected at one end to said other end of each lever, said links being pivotally connected at their other ends to said ladder structure, said one end of each lever projecting upwardly from its associated bearing when said ladder structure is in its operative position and projecting approximately horizontally from such bearing when said ladder structure is in its inoperative position, and a pair of dash pots arranged adjacent and outwardly of opposite sides of said frame, each dash pot comprising an upstanding cylinder pivotally connected at its lower end to one of said brackets and a piston in said cylinder pivotally connected at its upper end to said one arm of the associated lever eccentric to the trunnion thereof, said cylinder intermediate its ends being vented to the atmosphere whereby said piston is freely movable away from either end of said cylinder but is cushioned in its approach toward either end of said cylinder.

50 5. A folding stairway comprising a generally rectangular open frame adapted to be mounted in a ceiling and having end and side walls, a ladder structure hinged at one end to said frame adjacent the bottom of one end wall thereof to swing upwardly to an inoperative position within said frame and downwardly to assume an operative position, brackets fixed to the said side walls of said frame intermediate the ends thereof and projecting upwardly therefrom, horizontal bearings carried by the respective upper ends of brackets and having a common axis, a trunnion mounted in each bearing, a lever arm fixed at one end to each trunnion adjacent the outer end thereof, a counterweight carried by the other end of each lever arm, said lever arms and their counterweights lying wholly outwardly of the vertical planes of the side walls of said frame and having their counterweighted ends terminating adjacent said one end wall, an operating arm fixed to each trunnion at the inner end of its associated bearing and projecting generally toward the other end of said frame when said ladder structure is in inoperative position, and links connected between said operating arms and said ladder structure, each operating arm and its associated link lying between one of said side walls and the adjacent side of said ladder structure.

6. A folding stairway comprising a rectangular open frame having elongated parallel side frame members lying in parallel vertical planes, a plurality of ladder sections hinged end to end to swing to operative positions in alignment with each other and to folded inoperative superimposed positions, one of said ladder sections being hinged at one end thereof to one end of said frame, a bracket fixed to each side frame member intermediate the ends thereof and projecting thereabove and provided in their upper ends with aligned bearings, a lever provided intermediate its ends with a trunnion mounted in each bearing, one end of each lever being arranged wholly outwardly of its associated bearing and provided with a counterweight, the other end of each lever being positioned in a vertical plane adjacent and parallel to the vertical plane of the inner face of the associated side frame member, a link pivotally connected at one end to the free end of said other end of each lever inwardly thereof, each link having its other end pivotally connected to said one ladder section outwardly thereof at a point remote from the pivotal connection thereof with said frame, said counterweights lying outwardly of the outer faces of said frame members to swing in vertical planes free of such frame members and to assume positions substantially above said bearings when said ladder

10
15
